UNITED STATES PATENT OFFICE.

JOHN D. PEDERSEN, OF JACKSON, WYOMING.

FIREARM.

1,391,497.

Specification of Letters Patent. Patented Sept. 20, 1921.

Application filed December 13, 1919. Serial No. 344,676.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms which are usually designated as small arms, and a principal object of the invention is to furnish an improved grip-safety device particularly applicable to auto-loading and automatic pistols.

15 One class of small-arms to which my present improvements are applicable, includes the auto-loading pistols having a grip-stock, or handle-portion of the frame or receiver of the firearm, which is adapted to receive a 20 safety device operable by hand grip or compression.

An improved auto-loading pistol of this kind is described in my Patent No. 1,348,733, dated August 3, 1920, and granted on my 25 copending application (renewal) Serial No. 311,689, filed July 17, 1919, and the improvements herein described and claimed are illustrated in my said patent, but are not claimed therein. Therefore, for convenience of illustration, I have herein illustrated my present 30 improvements as arranged and applied to the particular kind of auto-loading pistol which is shown in the drawings of said patent, to which reference may be had.

35 The features of my grip safety device are that it is a grip or handle contained safety device arranged to prevent firing of the firearm by locking the firing-member or hammer and the trigger-sear, when my device is 40 in normal or safety position. Also, where the firearm is provided with a sliding breech-action comprising a firing-pin, to prevent discharge of the firearm by locking the breechaction to prevent contact between the 45 firing-pin and the cartridge, so that action of the firing-member or hammer on the firing-pin will not explode the cartridge. Another feature of my grip-safety device is that it neutralizes or reduces to a minimum 50 the "sting" upon the hand of the user of such firearm arising from the re-action of the hammer-spring or firing-spring of the firearm upon the sudden arresting of the firing-member or hammer when it strikes the firing-pin. Another feature of my grip safety

device is that it may be inserted in the firearm or removed therefrom and assembled or disassembled without the use of a tool, other than a nail or similar article having a relatively long and slender end.

60 Another feature of my grip-safety device is the arrangement of the grip-compressible member or grip-safety member, the firing-spring or hammer-spring and the firing member or hammer whereby the action of 65 such spring tends to hold the grip-safety member in its rearmost position when the firing-member or hammer is cocked, and also to hold one end of the grip-safety member in contact or engagement with the adjacent 70 portion of the firearm grip-stock. In the accompanying drawings, which illustrate certain embodiments of my grip safety device,

75 Figure 1, is a side elevation of a pistol provided with my grip-safety device.

Fig. 2, is a rear end view partly broken away, of a pistol provided with my grip-safety device.

80 Fig. 3, is a fragmentary side view on a larger scale than Fig. 1, of the rear portion of a pistol, partly broken away to show the parts comprising one embodiment of my grip-safety device.

85 Fig. 4, is a fragmentary side view on a larger scale than Fig. 1, of the rear portion of a pistol, broken away, to show the parts comprising another embodiment of my grip-safety device.

90 Fig. 5, is a detail side view of the means for securing my grip-safety device in the grip-handle or grip-stock of a pistol and for seating the main firing-spring or hammer-spring of the pistol, as related to the embodiment of my device shown in Fig. 3, and 95 used in different form in the embodiment shown in Fig. 4.

Fig. 6, is a detail plan view of the above 100 mentioned means for securing, on the line 7-7 of Fig. 3.

Fig. 7, is a detail plan view of a different form of said securing means as related to the embodiment of my grip-safety device shown in Fig. 4, on the line 6-6, of Fig. 4.

Fig. 8, is a detail side view of the spring-plug of said securing means used in both 105 embodiments of my grip-safety device.

Fig. 9, is a detail side view of the pivot pin used in both embodiments of my grip-safety device.

110

Similar reference characters are used to refer to similar parts throughout the several views.

My grip safety device comprises a frame 5 and a grip-safety member pivoted together by a transverse journal pin, the frame carrying a spring, which may be, and as shown is, a hammer-actuating or main firing-spring reacting upon a pin-locking slidable member 10, whereby the said two members are held assembled and said spring is held under compression, so that by sliding movement of said pin-lock the above-mentioned transverse journal-pin can be released and withdrawn, thereby releasing both said spring and the grip-safety member.

The grip-safety member, designated by G' is hand compressible or yieldable and is shown pivoted to the frame or receiver B 20 near the lower end of the handle-portion or grip-stock thereof, Figs. 3 and 4. The member G' closes the slot or space 2^s, Fig. 2, formed in the frame of the pistol to receive the grip-safety device, G', and which slot or 25 space is of use in assembling the details of the mechanism.

The grip-safety member G' is shown bored out at 7^a from below to receive the spring 8^e. The spring plunger 8^e and the spring plug 7^b 30 are shown operatively connecting with the spring 8^e, the spring plunger 8^e being located in a bored bracket b carried by the grip-safety member G'. The spring plug 7^b the upper end of which receives the lower end of the 35 spring 8^e, has an annular groove 7^e. The loose fitting pin g which pivots frame-end g' of the grip-safety member to the grip-stock portion of the frame or receiver B may also have an annular groove 7^e, Fig. 9, so 40 that when the spring 8^e is compressed by moving the spring plug 7^b upwardly, the grip-safety pin g may be inserted to connect pivotally the grip-safety member G' to the frame or receiver B. On releasing 45 the spring plug 7^b, the spring 8^e will move it downward until the top side of the annular groove in the plug bears against and interlocks with the pivot pin g in said groove thereof, and thus holds and locks said pin 50 against being moved endwise. Thus the member 7^b constitutes a pivot-locking device which, when the engaging faces are properly formed, positively dead-locks the pivot pin g in place, so that such pin cannot 55 be removed without first pushing upwardly the said member 7^b.

To remove the grip-safety pin g, it is only necessary to push the spring plug 7^b upward, to release this locking engagement. 60 The cupped top 8^m of the spring plunger 8^e receives the lower end of the spring rod 8^b the upper end of which is pivotally secured to the firing member or hammer H, the effect of the spring being to throw or 65 press the hammer H forwardly at all times.

When the hammer is in its cocked position (see Fig. 3) a line drawn through the pivot 8^d, which secures the spring rod 8^b to the hammer H, and through the grip-safety pin g, will pass in front of the center of the cupped or ball-and-socket engagement between the spring plunger 8^e and the spring rod 8^b. Hence the action of the spring 8^e tends to hold the grip-safety member G' in its rear-most position when the hammer 75 is cocked, and also holds one end, G², in contact or engagement with the adjacent portion of the firearm grip-stock, due to the engagement of the plunger 8^e with the inner side or face of the grip-safety member G'. 80

If the hammer H is released to its down or unlocked position, after the upper end of the grip-safety member G', as at G², is moved to its forward position, a line drawn through the spring rod pivot 8^d and the grip-safety pin g will pass substantially through the center of the cupped or ball-and-socket engagement between the spring plunger 8^e and the spring rod 8^b, so that the action of the spring 8^e will be to hold the 90 grip-safety member G', in its forward or compressed position.

A particular advantage of this latter arrangement is that the reaction of the spring 8^e on the grip-safety member G', due to the sudden arresting of the hammer H when it strikes the firing pin of the firearm, will be neutralized, so that my grip-safety device will have no tendency to sting the hand of the person using the firearm. 100

The top portion of the grip-safety member G', is bored out at 7^a, Fig. 3, to furnish clearance for the hammer H and the sear S, of the firearm, leaving a pair of side walls 7^e which are extended to provide a 105 pair of locking prongs 7^t. These prongs or lever arms 7^t are located outside of, and clear of, the rear end of the trigger-member F, of the firearm, and when the grip-safety member is in its rearward or safety 110 position, these lever arms are immediately below the bottom sides of the shoulders 14^c on the controller or disconnector N, which is thereby blocked against downward movement, the purpose of the controller N, being 115 to prevent or allow movement of the sliding breechaction of the firearm, and the controller N being movable upwardly and downwardly to accomplish this purpose. The controller N is so constructed and arranged 120 that when in suitable or upward position it will lock the sear S into the notch 8^j of the hammer H to prevent firing revolution or movement of the hammer; this being accomplished by a lever member n, pivotally 125 secured to the controller, which engages a spring projectible actuating means or actuator 14^m of the controller, and which lever member n also engages the sear S, the controller N being moved upward into such 130

locking position by the moving to firing position or cocking of the hammer H, and pressure of the actuating means or actuator 14^m.

5 The controller N, is located in an opening 15, in the frame or receiver B of the fire-arm, which forms a guiding means for the controller in its sliding movement. The controller N is moved downward when the 10 hammer H is moved to fired position by the ends 17ⁱ, of the sear S, which engage or bear down on the upper surface of the shoulders 14^p of the controller N.

It will be noted that if the notch 8ⁱ on the 15 hammer H should give away or be accidentally chipped or broken and rendered ineffective, the hammer in flying forward would be arrested during this movement and before it struck the firing pin of the fire-arm, since the sear S, would not be allowed to yield and revolve away from the hammer H for effective discharging movement, because of the engagement of the controller N with the sear S and the camming effect of the 20 eccentric cam surfaces 8^k on the hammer engaging the adjacent faces of the sear S, whereby the firing member or hammer is retarded or slowed down in movement from 25 firing position to fired position.

30 To release the hammer H to fire the arm the grip-safety member G' must be moved to its compressed or forward position prior to the pulling of the trigger F to discharge the firearm, as shown in outline in Fig. 3. 35 Such hand-grip pressure brings the locking arms 7ⁱ on the grip-safety forward from under the locking shoulders 14^e on the controller N to the recess 14^f, and thus allows the sear S to be revolved to release the hammer H. When the hammer is so released 40 the controller N will be moved downward, the grip-safety member G' being in its forward or compressed position. The grip-safety member G' therefore, when free from 45 external or hand-grip pressure, is an indicator of the hammer position, in that the grip-safety member is always in its forward or unlocking position, when the hammer H is forward, or in fired position, and will be 50 in its rearward or locking position, when the hammer is cocked or in firing position, provided in the latter case, the grip-safety member is allowed by the user of the fire-arm to assume this rearward or locking position.

The described arrangement of the controller N and the grip-operable safety member G' also affords means for holding the sliding breechaction of the firearm in re-tracted or rear position or open position, when the firearm is provided with a sliding breechaction. To do this the controller N is movable upwardly so that the upper end or top 14^a, thereof projects into the path of the 60 65 slidable breechaction of the firearm and in-

terferes with the forward sliding movement thereof. If the grip-safety member G' is released it will lock the controller N in such upward or interfering position so that the 70 slidable breechaction of the firearm will be held in its rear or open position. To allow the slidable breechaction of the firearm to go forward again to the closed position it is only necessary to compress the grip-safety member G', without however requiring the 75 trigger-member F to be pulled, to move the controller N downwardly out of such interfering position, and thereby permit the slidable breechaction of the firearm to move to its forward or closed position. 80

The hammer spring or firing spring plug 7^b, when my grip-safety device is assembled in the firearm, projects below the bottom line of the butt of the firearm, in this case a pistol, at or near the rear edge of the butt, 85 so that by taking the firearm in hand and bearing it down upon a table or other plane surface, the plug 7^b may be slid or moved inwardly in the butt far enough to permit the removal of the pivot g, which is freely-fitted in the frame or receiver B, thus enabling the mechanism to be disassembled without the use of tools, other than a suitably stout pin or slender nail to push out the 90 various journal pins of the firing-train 95 mechanism of the firearm.

In the embodiment of my grip-safety device shown in Fig. 4, the grip-safety pin g^a is arranged adjacent to the rear edge of the grip-handle or grip-stock of the firearm and 100 rearwardly of the spring-plug 7^b, the firing-spring 8^e thus being forward of the grip-safety pin g^a and located in a bored bracket b' supported by the grip-stock, but in other respects the parts and their arrangement are 105 similar, to those shown in Fig. 3. In Fig. 4, however, when the hammer is in its cocked position a line drawn through the pivot 8^d, which secures the spring rod 8^b to the hammer H, and through the grip-safety 110 pin g^a, will pass to the rear of the center of the cupped or ball-and-socket engagement between the spring plunger 8^c and the spring rod 8^b. But the action of the spring 8^e, will 115 be the same as hereinbefore stated in this 120 relation as to Fig. 3, except that a leaf spring 8^{e'} mounted on the grip-safety member G' and engaging the side face of the plunger 8^c is provided to return the end G² of the grip-safety member to engagement with the grip-stock after compression of the grip-safety member G'. 125

If the hammer H is released to its down or uncocked position, after the upper end of the grip-safety member G', as at G², is 130 moved to its forward position, a line drawn through the spring rod pivot 8^d and the grip-safety pin g^a will pass in front of the cupped or ball-and-socket engagement between the spring plunger 8^c and the spring 135

rod 8^b, the action of the spring 8^e being the same as stated in relation to the construction shown in Fig. 3.

Having thus described my invention, I 5 claim:

1. In a firearm, in combination, a frame comprising a grip-stock, a firing member, a grip-operable member engageable at the upper end thereof with said frame, a spring, 10 a plug insertible in the grip-stock from the butt end thereof through the butt end and providing a seat for said spring, a rod pivotally attached at one end to the firing member, a member movable in the longitudinal 15 line of the grip-stock by said spring and providing a seat for the other end of said rod, and a pin insertible in the grip-stock and engaging transversely the grip-operable member and said plug for providing 20 pivotal attachment of the lower end of the grip-operable member to the grip-stock.
2. In a firearm, in combination, a frame comprising a grip-stock, a firing member, a grip-operable member engageable at the upper end thereof with said frame, a spring, a 25 plug insertible in the grip-stock from the butt end thereof through said butt end and accessible from the butt end and providing a seat for said spring, a rod pivotally attached at one end to the firing member, a member movable in the longitudinal line of 30 the grip-stock by said spring and providing a seat for the other end of said rod, and a pin insertible in the grip-stock and engaging 35 transversely said plug and the grip-operable member for providing pivotal attachment of the lower end of the grip-operable member to the grip-stock.
3. In a firearm, in combination, a frame, a 40 plug insertible in the frame and under pressure when therein, and a pin insertible in the frame and engageable with the plug, the plug and pin being constructed and arranged each for retaining the other in the 45 frame.
4. In a firearm, in combination, a frame, a plug insertible in the frame and under pressure when therein, and a pin insertible in the frame and engageable with the plug, the 50 plug and pin being constructed and arranged each for retaining the other in the frame, and the plug being movable to position for releasing the pin for removal of the pin and plug from the frame.
5. In a firearm, in combination, a frame, a 55 plug of X-shape insertible in the frame and under spring pressure when therein, and a pin insertible in the frame and provided with a groove engageable with the plug between arms thereof whereby the plug and pin each retains the other in the frame.
6. In a firearm, in combination, a frame, a 60 plug of X-shape insertible in the frame and under spring pressure when therein, and a pin insertible in the frame and provided 65

with a groove engageable with the plug between arms thereof whereby the plug and pin each retains the other in the frame, the plug being accessible from the outside of the frame and movable to position for releasing 70 the pin for removal of the pin and plug from the frame.

7. In a firearm, in combination, a frame comprising a grip-stock, a grip-operable member engageable at one end thereof with 75 said frame, a plug insertible in the grip-stock, and a pin insertible in the grip-stock and engaging said plug and the other end of the grip-operable member for providing pivotal attachment of the grip-operable 80 member to the grip-stock, said plug and pin being constructed and arranged for each to retain the other in the grip-stock.

8. In a firearm, in combination, a frame comprising a grip-stock, a grip-operable 85 member engageable at one end thereof with said frame, a plug insertible in the grip-stock from the butt end thereof through the butt end, and a pin insertible in the grip-stock and transversely engaging said plug 90 and the other end of the grip-operable member for providing pivotal attachment of the grip-operable member to the grip-stock, said plug and pin being constructed and arranged for each to retain the other in the 95 grip-stock.

9. In a firearm, in combination, a frame comprising a grip-stock, a grip-operable member engageable at one end thereof with 100 said frame, a plug insertible in the grip-stock from the butt end thereof through the butt end and accessible from the butt end, and a pin insertible in the grip-stock and transversely engaging said plug and the other end of the grip-operable member for 105 providing pivotal attachment of the grip-operable member to the grip-stock, said plug and pin being constructed and arranged for each to retain the other in the grip-stock.

10. In a firearm, in combination, a frame 110 comprising a grip-stock, a grip-operable member engageable at one end thereof with said frame, a plug insertible in the grip-stock, and a pin insertible in the grip-stock and engaging said plug and the other end 115 of the grip-operable member for providing pivotal attachment of the grip-operable member to the grip-stock, said plug and pin being constructed and arranged for each to retain the other in the grip-stock and said 120 plug being movable from retaining position.

11. In a firearm, in combination, a frame comprising a grip-stock, a grip-operable member engageable at one end thereof with 125 said frame, a plug insertible in the grip-stock from the butt end thereof through the butt end, and a pin insertible in the grip-stock and engaging said plug and the other end of the grip-operable member for providing pivotal attachment of the grip- 130

operable member to the grip-stock, said plug and pin being constructed and arranged for each to retain the other in the grip-stock and the plug being accessible from said butt 5 end and movable to position for releasing the pin for removal of the pin and plug from the grip-stock.

12. In a firearm, in combination, a frame comprising a grip-stock, a grip-operable 10 member engageable at one end thereof with said frame, a plug insertible in the grip-stock from the butt end thereof through the butt end, and a pin insertible in the grip-stock and transversely engaging said 15 plug and the other end of the grip-operable member for providing pivotal attachment of the grip-operable member to the grip-stock, said plug and pin being constructed and arranged for each to retain the other 20 in the grip-stock and the plug being accessible from said butt end and movable to position for releasing the pin for removal of the pin and plug from the grip-stock.

13. In a firearm, in combination, a frame 25 comprising a grip-stock, a grip-operable member engageable at the upper end thereof with said frame and disengageable therefrom by grip-compression, a plug insertible in the grip-stock from the butt end thereof 30 through said butt end, a pin insertible in the grip-stock, and transversely engaging said plug and the lower end of the grip-operable member for providing pivotal attachment of said member to the grip-stock 35 for grip-compression of said member, the grip-operable member being spring actuated for returning the upper end thereof to engagement with said frame when grip-compression of said member is relieved.

40 14. In a firearm, in combination, a frame comprising a grip-stock, a bracket supported by the grip-stock, a grip-operable member engageable at the upper end thereof with said frame and disengageable therefrom by grip-compression, a plug insertible in the grip-stock from the butt end thereof through said butt end, a pin insertible in the grip-stock and engaging transversely 45 said plug and the lower end of the grip-operable member for providing pivotal attachment of the grip-operable member to the grip-stock for grip-compression of said 50

member, and a spring arranged and connected between said bracket and the grip-operable member for returning the upper 55 end of the grip-operable member to engagement with said frame when grip-compression of said member is relieved.

15. In a firearm, in combination, a frame comprising a grip-stock, a bored bracket 60 supported by the grip-stock, a firing member movable to firing position and to fired position, a sear engageable with the firing member, a slideable member operatively connected to the sear for locking the sear and 65 firing member in firing position and movable to unlocking position, a grip-operable member engageable at the upper end thereof with said frame and engageable with the slideable member for blocking the slideable 70 member in locking position when the upper end of the grip-operable member is so engaged, a spring in said bored bracket, a plug insertible in the grip-stock from the butt end thereof through said butt end and 75 received in the bored bracket and providing a seat for said spring, a rod pivotally attached at its upper end to the firing member, a plug in the bored bracket engaging the upper end of said spring and movable 80 thereby and providing a seat for the lower end of said rod, a pin insertible in the grip-stock and engaging transversely the first mentioned plug and the lower end of the grip-operable member for providing pivotal 85 attachment of the grip-operable member to the grip-stock for grip-compression of said member, and a spring arranged and connected between said bored bracket and the grip-operable member; the upper end of the 90 grip-operable member being disengageable from said frame and said slideable member being released for movement to unlocking position by grip-compression of the grip-operable member, and the upper end of the 95 grip-operable member, when said grip-compression is relieved, being returnable to engagement with said frame by pressure of the last mentioned spring on the grip-operable member.

JOHN D. PEDERSEN.
